UNITED STATES PATENT OFFICE.

ROBERT W. SCOTT, OF BOSTON, MASSACHUSETTS, ASSIGNOR TO SCOTT & WILLIAMS,
INCORPORATED, OF CAMDEN, NEW JERSEY, A CORPORATION OF NEW JERSEY.

DEVICE FOR KNITTING ON TRANSFERRED FABRIC SECTIONS.

1,194,674.

Specification of Letters Patent. Patented Aug. 15, 1916.

Application filed June 21, 1915. Serial No. 35,251.

To all whom it may concern:

Be it known that I, ROBERT W. SCOTT, a citizen of the United States, and resident of Boston, in the county of Suffolk and 5 State of Massachusetts, have invented certain new and useful Improvements in Devices for Knitting on Transferred Fabric Sections, of which the following is a specification.

10 My invention relates to automatic machines for knitting on transferred fabric sections. Such machines, having completed one article, are prepared to knit another by transferring by hand to their needles a previously knit fabric section. In my application Serial No. 807,535 filed December 18, 15 1913, I have shown described and claimed the mechanism for automatically casting off the product and leveling the needles of such a machine, for then stopping it, and for adjusting the machine automatically to begin knitting upon again starting it. In operation my said device still requires the operator to lift away from the needles and to return to 20 operative position at the needles certain parts obstructing access for the transfer operation during the period of stoppage between operations.

One object of my present invention is 30 further to reduce the skill and time required of the operator and so increase the product, by automatically moving away from the needles all obstructing parts at the end of one cycle of operations, and returning them 35 to operative position at the beginning of another cycle, after the transfer has been made.

Another object is to provide means for 40 moving the guard device, yarn-feed implements, and other upper parts of a circular knitting machine into and out of position for operation automatically, said means providing for holding the guard-device and attached parts in their inoperative position 45 when desired.

In the accompanying drawing, the figure 50 is a right-hand elevation, partly in vertical section, of so much of a knitting machine provided with my devices as is necessary to show the relation of the new parts to the machine improved.

A guard device, for instance such as the

latch guard ring 550 shown in the drawing, is provided with a lug or lugs 553 pivoted at 552 on a standard 401, said latch ring resting in a horizontal position on top of a standard 400 at the front of the machine, which standard may be grooved to receive a positioning gib 557 on the underside of a lug 556 forming a part of the latch ring. 60 The said device when so positioned is in the usual operative relation to the heads of needles *n* in the needle-cylinder 260, and said latch-guard device may carry such parts of the instruments coöperating with 65 the needles as may be desired to be placed near their heads, for instance the movable yarn-guides F, and a yarn severing mechanism 608, such as shown in my said application, and an internal needle presser 701, 70 such as shown described and claimed in my application Serial No. 3,126 filed January 19, 1915.

Actuation of the devices mentioned is effected through a series of thrust-bars 460 75 guided in fixed combs 451, 462 having free ends in contact with the respective devices F, 701 and 608 when the device 550 is in the operative position shown in full lines. As fully set out in my said applications one 80 of the bars 460 may be provided with a lug 46 for withdrawing a segment 370 to level the needles. Actuation of bars 460 for these purposes is effected by cams on a drum 120 intermittently moved through one revolution during each cycle of operations. The machine is provided with an automatic device for stopping (not shown), for instance as set out in said application 807,535, which 85 is timed to stop the machine when the line X of drum 120 shall have reached the series of bars 460. At this time the needles will have been freed of fabric and leveled to receive a transfer device loaded with a 90 previously knit fabric section.

A rigid stud 2 is fast in the latch-guard 550 and eccentric to its pivot 552, said stud taking into a hole in the upper end of a bent thrust-bar 4 guided in comb 451 so that the lower end of bar 4 rests near the surface of 100 drum 120 when the latch-guard is in operative position. A cam 5 is fastened on drum 120 so that a high part thereof is under bar 4 when the machine stops, the leading end 95

of cam 5 acting on 4, after the yarn has been withdrawn and severed to cast off the completed article, to rotate stud 2 and with it the latch-guard and its devices about pivot 552 5 as a center until the bottom of the latch-guard is at line Y, and the needles are freely accessible. A strong spring 6 extends between a stud 7 fast in the latch ring and a bolt passed through a hole in a bracket 9 10 and adjustably held by jam-nuts 10.

When cam 5 acts on bar 4, latch-guard 550 is not lifted so far as to carry stud 7 past the center 552 with respect to the line of action of spring 6, and, the transfer having been 15 made, further movement of drum 120 permits spring 6 to restore the devices which have been lifted out of the way to their operative positions. This takes place simultaneously with or previous to the operation 20 of devices F, 370 and 701 to begin knitting, as a first result of starting the machine.

I prefer to arrange the cams on drum 120 as shown so that cam 121 controlling the 25 yarn-guide F for use at the beginning of the next stocking and cam 503 controlling the segment 370 through lug 46 run from under their thrust-bars just prior to the return of guard 550 to operative position. A yarn guide F will therefore be in an operative 30 position when it returns with the latch-ring, and the yarn positioned between its end and the yarn severing and clamp device 608 will be entered between the moving needles by the motion of guard 550. Cam 520 for moving 35 the needle presser device 701 of my said application Serial No. 3,126 acts immediately following this time, prior to the motion of the first needle to knit, to cause it to take the yarn. The said arrangement avoids 40 necessity for accurately positioning the following end of the cam 121, and provides a yarn to begin knitting stretched between the clamp device and a yarn-guide, to insure its passage between the needles.

45 When it is desired at any time in the operation, or when the machine parts are in any position, the latch-guard may be manually lifted for access to the needles, the bar 4 being free to rise with it. If lifted so far, 50 for instance to bring its bottom to line Z, as to carry stud 7 past the center 552, the stress of spring 6 then serves to hold the lifted parts in their upper position.

While I have described my device in connection with a latch-needle machine, it will be understood that machines employing other types of needles are provided with overhead devices equivalent for the purposes of my present invention to the guard 550 and its attachments and that other known devices for casting off the fabric than means for removing or severing the yarn may be employed, and that my invention is

applicable without change to use in such machines or with such devices.

65

What I claim is:

1. A knitting machine having in combination needles, a guard device therefor, automatic stopping mechanism, and means for automatically moving the guard device 70 away from the needles prior to stoppage to permit access to the needles, and for automatically returning said device after starting the machine.

2. A knitting machine having needles, 75 leveling devices, and means for casting off the fabric and stopping the operation of the machine after casting off and after leveling, and also having a needle guard device in combination with automatic means for removing said guard device from the neighborhood of the needles prior to stoppage, and for returning said guard device to operative position during subsequent operation of the machine.

80

3. A knitting machine having in combination needles, a guard device, a movable yarn-feed guide on said device, automatic stopping mechanism, and automatic means for moving the guard device away from the 90 needles, for positioning the yarn-guide operatively, and for returning the guard device and positioned yarn-guide to operative relation with the needles when the machine is again started.

95

4. A knitting machine having in combination a needle guard ring, a spring holding said needle guard ring in position for normal operation, a pattern surface, and a connection from said surface for positively 100 moving said needle guard ring out of its normal position against the stress of said spring at predetermined times, said connection permitting manual movement of said guard ring.

105

5. A knitting machine having a needle guard device pivoted on a fixed part of the machine, a thrust-bar taking against a part of said needle guard device eccentric to said pivot, and means acting on said thrust-bar 110 to rotate said device about its pivot.

6. A knitting machine having in combination a pivoted latch ring, a spring reacting between a fixed part and a part of said latch ring eccentric to its pivot, a bar, and means for moving said bar to swing said latch ring about its pivot through an angle on one side of a line joining said latch ring pivot and said fixed part whereby said latch ring is automatically elevated and returned, the arrangement permitting manual elevation to hold the latch ring in an upper position 115 against the stress of said spring.

120

In testimony whereof, I have signed my name to this specification.

ROBERT W. SCOTT.
